CONTROL FOR A HEATING BLANKET

Walter E. Moore, St. Louis, Mo., assignor to Knapp-Monarch Company, St. Louis, Mo., a corporation of Delaware

Application July 20, 1956, Serial No. 42,307

Term of patent 14 years

(Cl. D26—5)

Figure 1 is a perspective view of a control for a heating blanket showing my new design;

Figure 2 is a front elevation view of the same; and

Figure 3 is a top plan view of the same.

I claim:

The ornamental design for a control for a heating blanket, as shown.
